United States Patent

Des. 235,123
Patented May 20, 1975

235,123

CANISTER OR SIMILAR ARTICLE

Walter B. Achenbach, Toledo, Ohio, assignor to
Owens-Illinois, Inc., Toledo, Ohio

Filed Oct. 23, 1973, Ser. No. 408,826

Term of patent 14 years

Int. Cl. D9—02; D7—07

U.S. Cl. D7—79

FIG. 2

FIG. 1

FIG. 3

FIG. 5

FIG. 4

FIG. 6

FIG. 8

FIG. 7

FIG. 9

FIG. 11

FIG. 10

FIG. 12

FIG. 1 is an elevational view of a canister or similar article embodying my new and ornamental design in the size and proportions of a tea canister;

FIG. 2 is a top plan view thereof;

FIG. 3 is a bottom view thereof;

FIG. 4 is an elevational view of a canister or similar article embodying my new and ornamental design in the size and proportions of a coffee canister;

FIG. 5 is a top plan view thereof;

FIG. 6 is a bottom plan view thereof;

FIG. 7 is an elevational view of a canister or similar article embodying my new and ornamental design in the size and proportions of a sugar canister;

FIG. 8 is a top plan view thereof;

FIG. 9 is a bottom plan view thereof;

FIG. 10 is an elevational view of a canister or similar article embodying my new and ornamental design in the size and proportions of a flour canister;

FIG. 11 is a top plan view thereof;
FIG. 12 is a bottom plan view thereof.

I claim:

The ornamental design for a canister or similar article, as shown and described.
